HANDLE FOR SPOONS, FORKS, &c.

No. 17,783.

Patented Oct. 11, 1887.

UNITED STATES PATENT OFFICE.

HENRY A. PISTORIUS, OF NEWBURYPORT, MASSACHUSETTS, ASSIGNOR TO
THE TOWLE MANUFACTURING COMPANY, OF SAME PLACE.

DESIGN FOR A HANDLE FOR SPOONS, FORKS, &c.

SPECIFICATION forming part of Design No. 17,783, dated October 11, 1887.

Application filed September 2, 1887. Serial No. 248,664. Term of patent 7 years.

To all whom it may concern:

Be it known that I, HENRY A. PISTORIUS, of Newburyport, in the county of Essex and State of Massachusetts, have invented and produced 5 a new and original Design for Handles of Spoons and other Table-Ware, of which the following is a full, clear, and exact description.

This design relates to the handles of spoons and other table flat ware, including fork and 10 ladle handles; and it consists in a novel ornamentation of the handle, as hereinafter described, and pointed out in the claim.

Reference is to be had to the accompanying photograph, which forms part of this specification, and which represents a face view of a 15 spoon having its handle ornamented in accordance with my design.

A is the handle, the marginal contour of which resembles that of other handles of various articles of table flat ware.

The design, which appears upon the face side

of the handle, represents a vine, B, running up and about and across the face of the handle, commencing with the inner and smaller end 25 of the latter, the leaves b of the vine appearing as if rolling over the side edges of the handle, and further represents a cornucopia or horn of plenty, C, as ensconced within the vine and as carrying fruit, d. All of these several 30 ornamental figures which make up the design have a raised appearance on the handle, the cornucopia with its fruit being upon the upper portion of the face of the handle.

1 claim—

The design for the handle of a spoon or other article of table flat ware herein shown and described, the same consisting of the vine B and the cornucopia C.

HENRY A. PISTORIUS.
